(57) **CLAIM**

The ornamental design for a dusting attachment for a broom, as shown and described.

DESCRIPTION

FIG. 1 is a front perspective view of a dusting attachment for a broom, showing my new design;

FIG. 2 is a front elevational view of FIG. 1;

FIG. 3 is a rear elevational view of FIG. 1;

FIG. 4 is a left-side elevational view of FIG. 1, the right-side elevational view being a mirror image thereof;

FIG. 5 is a top plan view of FIG. 1; and,

FIG. 6 is a bottom plan view of FIG. 1.

The broken lines in the figures depict portions of the dusting attachment for a broom that form no part of the claimed design.

1 Claim, 5 Drawing Sheets
